[57] CLAIM

The ornamental design for a spool for a fishing spinning reel, as shown and described.

DESCRIPTION

FIG. 1 is a front and left side perspective view of a spool for a fishing spinning reel, showing our new design;
FIG. 2 is a front and right side perspective view thereof;
FIG. 3 is a front elevational view thereof; the opposite side being a mirror image thereof; and a top plan view and a bottom plan view being identical thereof;
FIG. 4 is a right side elevational view thereof;
FIG. 5 is a left side elevational view thereof;
FIG. 6 is a central vertical cross-sectional view in FIG. 4;
FIG. 7 is a front and left side perspective view of a second embodiment of the spool for a fishing spinning reel; and,
FIG. 8 is a front and right side perspective view thereof.
